US00D919619S

(12) **United States Design Patent** (10) **Patent No.:** **US D919,619 S**
 (45) **Date of Patent:** ** *May 18, 2021

(54) **REMOVABLE BAND FOR A WATCH BODY**(71) Applicant: **Fitbit, Inc.**, San Francisco, CA (US)

(72) Inventors: **Irina Igorevna Kozlovskaya**, San Francisco, CA (US); **Benjamin Patrick Robert Jean Riot**, San Francisco, CA (US); **Anthony Gerald Kern**, Pleasant Hill, CA (US); **Derek Jenchia Loh**, San Carlos, CA (US); **Bernhard Wildner**, San Francisco, CA (US); **Junyong Park**, San Francisco, CA (US); **Jeffrey Andrew Fisher**, Mountain View, CA (US); **Patrick James Markan**, San Francisco, CA (US); **Yu Chuan Kang**, Taipei (TW); **Stephen Ronald Smilovitz**, Belmont, CA (US)

(73) Assignee: **Fitbit, Inc.**, San Francisco, CA (US)

(*) Notice: This patent is subject to a terminal disclaimer.

(**) Term: **15 Years**(21) Appl. No.: **29/727,222**(22) Filed: **Mar. 9, 2020****Related U.S. Application Data**

(62) Division of application No. 29/645,397, filed on Apr. 25, 2018.

(51) **LOC (13) Cl.** ..... **14-02**(52) **U.S. Cl.**USPC ..... **D14/344**(58) **Field of Classification Search**

CLAIM

The ornamental design for a removable band for a watch body, as shown and described.

DESCRIPTION

This application is related to application Ser. No. 29/635,224 filed Jan. 29, 2018, which is incorporated entirely by reference herein for all purposes.

FIG. 1 is a top, plan view of a first embodiment of a removable band for a watch body showing our new design FIG. 2 is a bottom plan view of FIG. 1.

FIG. 3 is a right side elevation view of FIG. 1.

FIG. 4 is a left side elevation view of FIG. 1.

FIG. 5 is a back side elevation view of FIG. 1.

FIG. 6 is a front side elevation view of FIG. 1.

FIG. 7 is a close-up side elevation view of the attachment surface of FIG. 6.

FIG. 8 is an isometric view of FIG. 7.

FIG. 9 is a cross sectional view taken along line 9-9 of FIG. 12 directionally upward.

FIG. 10 is a cross sectional view taken along line 10-10 of FIG. 12 directionally downward.

FIG. 11 is a cross sectional view taken along line 11-11 of FIG. 12.

FIG. 12 is a close up side elevation view with lines showing the location of the cross sectional views.

FIG. 13 is a top, plan view of a second embodiment of a removable band for a watch body showing our new design FIG. 14 is a bottom plan view of FIG. 13.

FIG. 15 is a right side elevation view of FIG. 13.

FIG. 16 is a left side elevation view of FIG. 13.

FIG. 17 is a back side elevation view of FIG. 13.

FIG. 18 is a front side elevation view of FIG. 13.

FIG. 19 is a close-up side elevation view of the attachment surface of FIG. 18.

FIG. 20 is an isometric view of FIG. 19.

FIG. 21 is a cross sectional view taken along line 21-21 of FIG. 24 directionally upward.

FIG. 22 is a cross sectional view taken along line 22-22 of FIG. 24 directionally downward.

FIG. 23 is a cross sectional view taken along line 23-24 of FIG. 24.

FIG. 24 is a close up side elevation view with lines showing the location of the cross sectional views.

FIG. 25 is a top, plan view of a third embodiment of a removable band for a watch body showing our new design FIG. 26 is a bottom plan view of FIG. 25.

FIG. 27 is a right side elevation view of FIG. 25.
FIG. 28 is a left side elevation view of FIG. 25.
FIG. 29 is a back side elevation view of FIG. 25.
FIG. 30 is a front side elevation view of FIG. 25.
FIG. 31 is a close-up side elevation view of the attachment surface of FIG. 30.
FIG. 32 is an isometric view of FIG. 31.
FIG. 33 is a cross sectional view taken along line 33-33 of FIG. 36 directionally upward.
FIG. 34 is a cross sectional view taken along line 34-34 of FIG. 36 directionally downward.
FIG. 35 is a cross sectional view taken along line 35-35 of FIG. 36; and,
FIG. 36 is a close up side elevation view with lines showing the location of the cross sectional views.
The features shown in broken lines in the drawing depict portion of the removable band for a watch body that form no part of the claimed design. The dash dot dash lines represent unclaimed borders.
